Addison Smith.

UNITED STATES PATENT OFFICE.

ADDISON SMITH, OF NEW YORK, N. Y., ASSIGNOR TO HIMSELF AND JAMES M. SAYRE, OF SAME PLACE.

IMPROVEMENT IN GAS-COMPENSATORS.

Specification forming part of Letters Patent No. 40,085, dated September 22, 1863.

To all whom it may concern:

Be it known that I, ADDISON SMITH, of the city, county, and State of New York, have invented certain new and useful improvements in the apparatus known as a "Gas-Compensator," to regulate the pressure of gas while being drawn from the retort by exhausters; and I do hereby declare the following to be a full, clear, and exact description thereof, reference being had to the accompanying drawings, figures, and letters of reference thereon, making part of this specification.

Of the said drawings, Figure 1 represents a front elevation, and Fig. 2 a vertical section.

Similar letters of reference indicate like parts in all the drawings.

My invention is designed as an improvement upon the invention patented by Philip W. Mackenzie, of Jersey City, New Jersey, March 4, 1862, which patent was duly assigned to me by said Mackenzie.

In Mackenzie's compensator the corrugated metal plates, after being a short time in use, crack and break from the contraction and expansion of the metal or other causes, and thereby the efficiency of the invention is greatly impaired.

My invention is designed to obviate this difficulty; and it consists, first, in a combining with a cylinder (secured between gas-pipes) provided with posts and a valve mechanism an inverted dish and a fluid-joint for operating the valves and regulating the pressure of the gas, as will be more fully set forth herein-after.

The second part of my invention consists in the combination, with an inverted dish and fluid-joint, of a double rotary valve, whereby a small movement of the inverted dish and its connections causes the valve to give increased communication between the pipes, as will be fully set forth.

To enable others skilled in the art to make and use my invention, I will describe the construction and operation thereof.

A A' represent the main pipes leading from the retorts, and between which the gas-exhauster is placed. B B' are pipes leading from the pipes A and A' and connecting with the valve-cylinder C. On this cylinder is secured a vertical column, D, to the upper part of which is secured a disk or cylinder, F, pro-

vided with an inner cylinder, which forms a channel for the fluid-joint, as plainly shown in Fig. 2.

In the column D there is a box, f, for the lower end of the vertical rod G, and also another box, e, which keeps the rod in position and allows it to slide freely. This rod G has a screw-thread cut thereon, upon which is placed a nut, 6, at the lowest point.

The inverted dish H is then placed upon the spindle G with a packed joint and clamped in position by the nuts 5 and 6. A bar, e, (to the ends of which are attached the valve-rods a,) is then secured upon the spindle G by the nuts 3 and 4, and the arched spring d is adjusted by the nuts 1 and 2. The ends of the arched spring are slotted and rest upon the ears j, and are kept in place by pins i, inserted in the ears, fitting the slots. The channel J is filled, as indicated in the color Fig. 2, to make a sealed joint. Any fluid may be used, but I prefer and use quicksilver as the best, as it does not evaporate or become stale.

The cylinder C is provided with a rotary double valve, E, secured upon a rod, I, which is packed in the cylinder-heads sufficiently tight not to emit gas. Secured to this rod outside the cylinder-head is an index-hand, h, and the arms b b, (one on each end of the cylinder,) to which connecting rods a pass to the lever e and are secured and adjusted by nuts.

Operation: The operation will be as follows: In Fig. 2 the communication between the pipes A B, cylinder-posts, and column D, and inverted cup H is open and unobstructed, while on the other side of the pipes are closed. The valve mechanism is adjusted so that the valve stands in the position shown in Fig. 2, and the index-pointer stands at o. The gas is drawn from the retorts through the passages A A' by the exhauster, (which is located between the pipes, but not shown,) as indicated by the arrows. If the exhauster is at any time driven too fast, reducing the pressure on the retorts below the desired point, the cup H is depressed by the decreased pressure in the cup and the valve thrust open, allowing the gas to pass through the ports g g, as indicated by the arrows in the pipes B and B', to supply the amount demanded by and due to the increased speed of the exhauster.

By means of the nuts on the screw G and

the slotted arms *b*, the valve is adjusted on the verge of the post *g*, so that the least depression of the inverted cup *H* will operate the valve *E*, and thus regulate automatically the pressure of gas and prevent the formation of a vacuum. The great advantage of a double valve is that a small amount of motion of the inverted cup gives a greatly-increased communication between the pipes and admits a greater amount of gas to pass from one pipe to the other, and more quickly and evenly regulates the pressure.

I claim—

1. Combining with a cylinder provided with posts and a valve mechanism, substantially

as described, the inverted cup and fluid-joint for operating the valves and regulating the pressure of gas, substantially as described and set forth.

2. The combination, with an inverted cup and fluid-joint, of a double valve, whereby a small movement of the inverted cup causes the valve to give increased communication between the pipes, and thereby more quickly and evenly regulates the pressure of gas, substantially as described and set forth.

ADDISON SMITH.
